W. H. MONROE

COOLING DEVICE

Filed March 29, 1927

UNITED STATES PATENT OFFICE.

WILLIAM H. MONROE, OF COLFAX, IOWA.

COOLING DEVICE.

Application filed March 29, 1927. Serial No. 179,382.

The object of my invention is to provide a cooling device of simple, durable and inexpensive construction, adapted to be mounted in a cabinet supported over a well or hole in the ground, in such a manner that the cooling device may be elevated and lowered into or out of said well for the purpose of cooling food stuff or other material that may be placed in the cooler.

More specifically it is the object of my invention to provide in that type of cooler employing a cabinet supported above a well for receiving a food container, improved means for elevating and lowering the food container into and out of the well.

A further object is to provide in connection with the cabinet guide members secured to said cabinet and projected downwardly into the well, having slidably mounted thereon the food container, said food container being constructed with a closed bottom so that in case water should run into the well after the container has been lowered therein, the same will float and be prevented from tipping over.

A further object is to provide an improved guide which may be easily and quickly spliced to adapt the device to be used in wells of various depths and in connection therewith improved means for slidably mounting the food container to the guides.

My invention consists in the construction, arrangement and combination of the various parts of the device, whereby the objects contemplated are attained, as hereinafter more fully set forth, pointed out in my claim, and illustrated in the accompanying drawings, in which:

Figure 1 is a sectional view of a well showing in front elevation my improved device and the manner in which it is mounted in said well.

Figure 2 is an enlarged, detail, horizontal, sectional view taken through the cabinet and the container.

Figure 3 is a vertical sectional view taken on the line 3—3 of Figure 2.

Figure 4 is an enlarged, detail, sectional view showing the manner in which one of the guide members is mounted to the cabinet.

Figure 5 is a perspective view of two adjoining guide sections showing the manner in which they are spliced together.

The numeral 10 indicates a well or suitable hole in the ground, which may be of any desired depth, and provided with a platform 11, and said platform 11 being provided with

a rectangular opening 12. Mounted on the platform and above the opening 12 is a cabinet 13 having sides, a back and top member, the front being provided with a door 14. The upper end of the cabinet 13 having a windlass 15 operated by a hand crank 16. Secured to the inner surface of each of the side members of the cabinet 13 is a block 17, said blocks being arranged vertically and near the upper end. The lower ends of said blocks terminate at a point about midway between the ends of the side members.

Secured to each of the blocks 17 is a vertically arranged guide rail 18, each of which is made preferably of channel iron with their flanges extending inwardly. The lower ends of the members 18 are connected by a cross member 19. The channels are secured to the blocks 17 by suitable bolts 20. The bolts 20 form the only means of mounting the guide rails. Mounted between the guide rails 18 is the cooler 21, which comprises a substantially rectangular food cabinet formed preferably of galvanized sheet metal, having a back 22, side members 23, a top 24, bottom 25 and a short front member 26 projecting upwardly from the bottom 25 so that a watertight container is provided in the lower end of the cabinet. That portion of the front above the member 26 is closed by a door 27 slidably mounted in guideways 28, said door being adapted to slide downwardly in front of the member 26 and to be limited against downward movement by means of a cross member 29, the ends of which are secured to the side members 23 of the cabinet, said cross member being mounted in front of the door.

The downward movement of the said door is limited by means of a handle 30, secured near the upper end of said door, engaging the cross bar 29 when the door is at its lower limit. A spring catch 31 is provided for supporting the door in its elevated and closed position. The cabinet or food container 21 is provided with the ordinary shelves 32. The lower shelf is supported above the upper edge of the front member 26 a considerable distance so that food may be passed to the compartment in the lower end of the container and when so placed therein may be supported below the water level when the container is floating. This greatly assists in keeping the food thus placed cool.

The container 21 is slidably mounted between the guides 18 by means of brackets comprising flanges 33 arranged in pairs and pro-

jected outwardly from the side members of said container in such a manner as to receive the guides 18 between them, in the manner clearly illustrated in Figures 1 and 2. The outer ends of the flanges 33 are provided with bolts 34 designed to hold the guide rails between said flanges. One set of the flanges 33 is mounted on the lower end of each of the side members, and another set is mounted at a point midway between the upper and lower ends of said side members. By this arrangement the food container is free to slide upwardly and downwardly adjacent to said guides and to always be supported in an upright position, even when floating. The guides also serve to prevent excessive swinging of the food container when lowered in the well.

The container 21 is elevated and lowered by means of a cable 35, one end of which is secured to the top of the cabinet 13, while the other end is wound about the windlass 15, said cable passing through a pulley 36 supporting the food container by means of a bracket 37 mounted on the upper end of said food container. A cover 38 is provided for the opening 12 in the platform 11. This cover 38 is provided with an opening 39 through which the bracket 37, the pulley 26 and the cable 35 may extend. The said cover 38 is elevated from the opening 12 by engaging the top end of the food container as the same is moved into position in the cabinet, the said cover 38 permitted to rest on the platform 11 as the said container is lowered into the well, thereby providing means for automatically closing the opening 12.

When it is desired to splice the rails 18, the two ends of the rails are placed together and a splicing block 40 placed in the channel and riveted into position by suitable rivets 41, in the manner clearly illustrated in Figure 5. This provides means whereby the said guide rails may be spliced and at the same time maintain the symmetrical contour of the outer surface of the rail to permit the members 33 to move freely past said joint.

Thus it will be seen that I have provided a simple and inexpensive food cooler which may be used in either a dry well or one containing water, and when used in the latter, the food chamber may be partially submerged if so desired, thereby greatly increasing the cooling effect. By providing the water tight compartment in the bottom of the cooler,

means is provided for automatically floating the container in case the water should rise within the well while the cooler is supported therein, or in case water should accidentally run into the dry well.

By providing the guide rails 18 the food container is supported against tipping while floating.

An important feature of my invention lies in the flange members 33 being so arranged that the guide rails are always supported in operative relation with said food container. The bolts 34 provide means whereby the members 33 will always be retained in proper operative relation with the guide rails.

I am well aware that it is not new to provide guide rails for food containers, but so far as I am aware no means have been provided for retaining a slender guide rail in operative relation with the container in such a manner that the guide rails cannot spring outwardly and disengage the guide grooves. This heretofore has been a serious handicap in devices of this kind, inasmuch as it has been necessary to provide stiff and rigidly mounted guide rails so they may be retained in operative relation with the coating members of the container. By providing enclosed brackets for the guide rails, I have provided means whereby a very light and inexpensive guide rail may be utilized, such as a three-fourths or one inch stock channel iron. The same being supported entirely from the cabinet, provides means whereby the device may be easily and quickly installed.

I claim as my invention:

A cooler comprising a cabinet, guide rails depending from said cabinet, adapted to be suspended in a well, a food container slidably mounted between said guide rails, said food container comprising a substantially rectangular cabinet having a back, sides, top and bottom members, and a short front member from the bottom end of said container, the upper portion of said front being provided with a door, the upper end of said container being provided with shelves, the bottom shelf being supported a considerable distance above the upper edge of the front member to permit food to be placed in the lower end of said container, the lower end of said container being sealed to provide a float for said container.

Des Moines, Iowa, March 24, 1927.

WILLIAM H. MONROE.
